UNITED STATES PATENT OFFICE.

WILLIS F. WALKER, OF SEISHOLTZ, PENNSYLVANIA.

RAILWAY-TIE.

1,250,734.

Specification of Letters Patent. Patented Dec. 18, 1917.

Application filed May 3, 1917. Serial No. 166,209.

To all whom it may concern:

Be it known that I, WILLIS F. WALKER, a citizen of the United States, residing at Seisholtz, in the county of Berks and State of Pennsylvania, have invented a new and useful Railway-Tie, of which the following is a specification.

The subject of this invention is a railway tie, and the objects of the invention are, first, to provide a metal tie having a composition filler, second, to provide metal parts combining strength with lightness, third, to provide reinforced pockets for the reception of track fastening means, and fourth, to provide a simple and efficient tie.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

One practical embodiment of my invention is shown in the accompanying drawing, wherein:—

Fig. 1 is a plan view of a tie, the central portion broken away.

Fig. 2 is a side elevation of a portion of the tie showing the track seat.

Fig. 3 is a vertical cross section through one of the brace plates.

Fig. 4 is a central horizontal section of a tie at that portion shown in Fig. 2.

Referring to the drawings by numerals:—

The tie is constructed of I-beams 1—1 spaced apart by the tie plates 2, which are preferably formed of short sections of I-beam. The laterally extending edges 3 of each tie plate 2, which contact the web of each I-beam 1, are secured to the web by rivets, or otherwise. A reinforcing plate 5 is secured to the inner face of the web of each I-beam 1 at the point where the track is seated. Each plate 5 is formed with angularly disposed ends 6, and apertures 7 adapted to aline with apertures 8 formed in the web of each I-beam 1.

Concrete, indicated at 9, is filled in between the I-beams 1, and there is formed in this concrete, adjacent the apertures 7 and 8, openings 10, which extend through 55 and across the space between the I-beams 1. This permits the tie to be reversed end for end, and also with respect to the upper and lower faces. The edges 6 of the reinforcing plates serve to reinforce and retain the 60 concrete surrounding these openings 10. U-bolts 11 pass through the alining apertures 7 and 8 and the openings 10 and engage gripping members 12 for the purpose of binding a rail 13 in place upon the tie. It 65 will be noted that the apertures 7 and 8 are situated equidistant from the upper and lower faces of the tie. This is rendered necessary by the fact that the tie is reversible, as heretofore set forth. One end of the 70 U-bolt is inserted through the apertures from the outside and the bolt drawn into place as shown.

It is thought that the assembling and operation of the device is amply apparent 75 from the foregoing without any further and special description thereof.

Having described my invention, what I claim as new and desire to secure by Letters Patent, is:—

1. A railway tie, comprising spaced I-beams, spacing plates extending between and secured to the webs of the I-beams, and a filler packed between the beams and surrounding the spacing plates. 80

2. A railway tie, comprising beams provided with apertures, a filler between the beams having openings communicating with the apertures, and reinforcing plates secured to each beam and extending into the 90 openings. 85

3. A railway tie, comprising beams provided with apertures adapted to receive a rail securing element, a filler between the beams having openings communicating with 95 the apertures, reinforcing plates secured to each beam, and angularly disposed ends on each plate extending into the openings to support and retain the filler.

4. A railway tie, comprising spaced I-beams provided with apertures, spacing plates between the beams and secured to the 100

web of each beam, a filler between the beams provided with openings communicating with the apertures and opening at opposite faces of the tie, and reinforcing plates secured to each beam and extending into the openings.

In testimony that I claim the foregoing as

my own, I have hereto affixed my signature in the presence of two witnesses.

WILLIS F. WALKER.
